UNITED STATES PATENT OFFICE.

CLARENCE A. HART, OF RACINE, WISCONSIN.

DEVICE FOR REMOVING BURS FROM PIPES.

No. 909,182.

Specification of Letters Patent.

Patented Jan. 12, 1909.

Application filed April 9, 1908. Serial No. 426,021.

To all whom it may concern:

Be it known that I, CLARENCE A. HART, a citizen of the United States, residing at the city of Racine, county of Racine and State of Wisconsin, have invented new and useful Improvements in devices for Removing Burs from Pipes, of which the following is a specification.

My invention relates to improvements in devices for removing burs from pipes.

The object of my invention is to provide a device which can be rotated around the cut end of a pipe and which will effectually smooth or press out the bur or burs formed on the inner and outer surfaces during the cutting operation.

In the following description reference is had to the accompanying drawings in which,—

Figure 1 is a side view of my invention. Fig. 2 is a front elevation showing the same applied to a pipe which is illustrated in longitudinal section in this view and in cross section in Figs. 1 and 3. Fig. 3 is a side view illustrating a modified form of construction.

Like parts are identified by the same reference characters throughout the several views.

The supporting member A is provided with a fixed mandrel B at one end which is adapted to be inserted in the end of the pipe C. The mandrel B is provided with a rounded face b which is socketed and provided with rollers D, suitably journaled in the sockets and adapted to bear upon the inner surfaces of the pipe at its end margin, the rollers being in a position to extend across the bur or inwardly projecting flange formed on the pipe during the cutting operation. A movable member F is pivoted to the supporting member A at f. This member F is also socketed and provided with a roller G which is journaled therein in a position to bear upon the outer edge or end margin of the pipe C, preferably in a radial line extending from the center of the pipe between the rollers D. The roller G is moved inwardly and pressed against the pipe by means of a screw threaded rod H which has threaded engagement in an aperture formed in the outer end of the member A with the inner end of the rod H in a position to bear against the outer or free end of the member F in the rear of the roller G.

This rod H also serves as an operating handle and is preferably provided with a cross piece

I at its outer end to facilitate turning it in its screw threaded bearings.

The device having been adjusted to the pipe in the position shown in Fig. 1 and the rod H having been turned inwardly to engage the end of the pipe forcibly between the rollers D and G, the device is then rotated around the pipe by the operator until the bur is removed. The operation of removing the bur may be performed during a single rotation of the tool or if desired a series of successive rotations may be performed and the roller G additionally tightened upon the bur after each rotation.

Referring to Fig. 3 it will be observed that a blade J is substituted for the roller G in the member F. This blade may be formed of hardened metal and may be removably inserted in a dove-tailed groove in the member F with one edge projecting preferably in a slightly trailing position as shown.

Having thus described my invention what I claim as new and desire to secure by Letters Patent is,—

1. In a device of the described class, the combination of a supporting member, a mandrel thereon adapted to enter the end of a pipe, a movable member pivoted to the supporting member in a position to receive the wall of the pipe between it and said mandrel, a screw having threaded bearings in the supporting member and arranged with one end in registry with the outer or free end portion of the movable member, and a bur remover, mounted on said movable member.

2. In a device of the described class, the combination of a supporting member and two laterally projecting members, one rigidly and the other pivotally connected with the supporting member, and adapted to receive the wall of a pipe between them, a roller carried by the pivoted member in a position to bear upon the margin of the pipe, and means for pressing said roller forcibly against the pipe.

3. In a device of the described class, the combination of a supporting member and two laterally projecting members, one rigidly and the other pivotally connected with the supporting member, and adapted to receive the wall of a pipe between them, a roller carried by the pivoted member in a position to bear upon the margin of the pipe, and means

for pressing said roller forcibly against the pipe, said rigid member being provided with a pair of rollers, arranged to bear upon the inner surface of the pipe at its margin and on 5 opposite sides of the point of first mentioned roller pressure.

4. In a device of the described class, the combination of a supporting member and two laterally projecting members, one rigidly 10 and the other pivotally connected with the supporting member, and adapted to receive the wall of a pipe between them, a roller car-

ried by the pivoted member in a position to bear upon the margin of the pipe, and means for pressing said roller forcibly against the 15 pipe, said pressing means comprising a screw threaded rod having its outer portion extended to form a handle.

In testimony whereof I affix my signature in the presence of two witnesses.

CLARENCE A. HART.
